Application May 26, 1930, Serial No. 455,816
Renewed August 10, 1934

9 Claims. (Cl. 123—179)

This invention relates to starters for internal combustion engines and more particularly to starters of the inertia type.

One of the objects of the present invention is 5 to provide a simple, novel and reliable starter for internal combustion engines in which the starting operation is performed by the application to a rotatable member of the engine of energy which has been previously accumulated and stored in a 10 rotatable inertia member of the starting apparatus.

Another object is to provide an engine starter 15 of the inertia type in which novel actuating means are employed for rotating the inertia member and storing energy therein.

A further object is to provide an inertia starter 20 which is characterized by the use of a fluid under pressure for actuating the inertia member of the starting mechanism.

Another object is to provide an engine starter 25 of the type embodying an inertia member and actuating means for storing energy therein, in which the source of energy thus stored is an explosive cartridge.

A still further object is to provide an engine 30 starter of the inertia type which is characterized by the provision of novel, fluid pressure operated, actuating means for rotating and storing energy in the inertia member in which the fluid pressure is generated by an automatic cartridge exploding mechanism.

These and other objects will appear more fully in the detailed description of the invention which follows. Although only one embodiment of the 35 present invention is illustrated in the accompanying drawing, it is to be expressly understood that the drawing is for the purpose of illustration only and is not to be construed as a limitation of the scope of the invention, reference 40 being had for this purpose to the appended claims.

In the drawing:

Fig. 1 is a side view partly in section of one embodiment of the present invention;

Fig. 2 is a sectional view taken on the line 2—2 45 of Fig. 1; and

Fig. 3 is a plan view partly in section taken on line 3—3 of Fig. 1.

Referring now to the drawing wherein like reference characters indicate like parts throughout 50 the several views, the embodiment of the present invention shown in Fig. 1 comprises a rotatable inertia member, novel means for actuating the inertia member including a fluid pressure engine and automatic pistol means for producing the 55 fluid pressure therefor, and means including a

gear train and drive for transmitting the energy stored in the inertia member to a member of the engine to be started. The inertia member and energy transmitting means are housed in a casing 4 of suitable form, having a flange 5 which 5 is removably secured to a portion of the engine casing 6 by any suitable means such as bolts 7. Casing 4 is irregularly shaped and, as indicated in Fig. 1, comprises two approximately cylindrical contiguous portions. The upper portion provides a housing and bearing for a rotatable inertia member 8, preferably in the form of a flywheel, which is rigidly secured as by a key 9 and lock nut 10 to a short shaft 11, said shaft being suitably journaled in casing 4 by means of a bearing boss 12 and ball bearings 13. A pinion 14 is formed on the extremity of shaft 11 opposite to the flywheel 8, the teeth of said pinion terminating adjacent the ball races of bearings 13 and an annular retaining ring 15 secured to boss 12 as 20 by screws 16 to hold said bearings and shaft in their proper operative positions within the casing.

Flywheel 8 is preferably of small size and light weight, and is adapted for rotation at very high speed, the energy stored in the rapidly rotating 25 flywheel being transmitted preferably through a train of reduction gearing and a yieldable driving connection to a member of the engine to be started. In the form shown, pinion 14 which is formed integrally with the outer end of shaft 30 11 meshes with a gear 17 which is rotatably mounted as by means of a roller bearing 18 on a stub shaft 19 which is suitably journaled in a portion of casing 4. The hub of gear 17 is provided with gear teeth constituting a pinion 20 35 which meshes with a large external gear 21 having a hub 22 which is suitably supported on a hollow shaft 23 in a manner to be hereinafter described. Hub 22 of gear 21 is also provided with gear teeth constituting a pinion 24 which in turn 40 meshes with a plurality of planetary gears 25, preferably three in number, one of which is shown in section in Fig. 1. These planetary gears are rotatably mounted on the outer face of a barrel-shaped member 26 which is rotatable within casing 4 in the portion adjacent engine casing 6, the bearings for the planetary gears comprising ball bearings 27 surrounding sleeves 28 which are countersunk into the face of barrel 26 and secured thereto as by screws 29. An annular retaining 45 ring 30, which is U-shaped in cross-section, is secured under the head of screws 29 and retains the planetary gears in their proper position on their bearings and in operative meshing relation with an internal ring gear 31 which is secured 50 55

to casing 4 by any suitable means including a dowel pin 32 which is inserted in corresponding recesses in casing 4 and gear 31 for the purpose of absorbing the thrust developed by the meshing of planetary gears 25 with the stationary internal gear 31.

The rotation of flywheel 8 may thus be transmitted through a reduction gear train constituted by pinion 14, gear 17, pinion 20, gear 21, pinion 24, planetary gears 25, and ring gear 31 to the barrel 26. The rotation of the barrel 26 is in turn suitably transmitted, preferably through a yieldable driving connection, to a clutch jaw 33 which is adapted to be shifted axially into driving engagement with and to crank a corresponding clutch jaw 34 formed on a member of the engine to be started. In the form shown, an interiorly threaded nut 35 is positioned in barrel 26 and is drivably connected therewith by means of a friction clutch comprising a plurality of friction discs 36, alternate discs being splined to the interior surface of barrel 26 and to the exterior surface of nut 35. The discs 36 are held between an outer spacing ring 37 which is interposed between the outermost disc and the inner face of barrel 26, and an inner spacing ring 38 which is interposed between the innermost disc and a collar 39 formed on the nut 35. Discs 36 are resiliently urged into frictional engagement with one another by means of a plurality of coil springs 40 which bear at their inner ends against a plate 41 adjacent collar 39 and spacing ring 38, and exert their thrust against a nut 42 which is threaded into the outer end of barrel 26, and which provides a means for adjusting the torque transmission limit of the friction clutch. If desired, an annular ring 43 provided with a plurality of studs 44 may be employed to maintain springs 40 in spaced relation within the barrel.

A short screw shaft 45 is positioned within nut 35 and is exteriorly threaded to engage the threads formed in the interior of the nut, while the outer end of said screw shaft is splined to engage the interiorly splined hub 46 of clutch jaw 33. Any rotation of barrel 26 will therefore be transmitted through the friction clutch to nut 35 and thence by means of screw shaft 45 to clutch jaw 33.

Suitable means are also provided for moving the driving clutch jaw 33 into engagement with engine clutch jaw 34, and in the form shown comprises a rod 47 which extends centrally through screw shaft 45 and clutch jaw 33, and is provided on its inner end with a nut 48 which limits the inward movement of clutch jaw 33. A coil spring 49 is provided surrounding rod 47 at its inner end and interposed between the outer face of clutch jaw 33 and the bottom of a recess formed in the inner end of screw shaft 45, for the purpose of yieldingly urging the clutch jaw inward. Rod 47 is also provided with a shoulder 50 engaging the outer end of screw shaft 45, so that when said rod is pushed toward the left as viewed in Fig. 1 by means hereinafter described, the threaded engagement between shaft 45 and nut 35 causes said shaft to move toward the left, compressing spring 49 and resiliently urging clutch jaw 33 into engagement with clutch jaw 34. A nut 51 is provided on the outer end of screw shaft 45 and is adapted to abut a shoulder formed on the interior of nut 35 for the purpose of limiting the inward movement of screw shaft 45. When the engine to be started starts under its own power, clutch jaw 34 over-

runs clutch jaw 33 and the inclined faces of the teeth of said jaws are effective to force clutch jaw 33 outwardly, or to the right as seen in Fig. 1, out of engagement with clutch jaw 34 and to restore the apparatus to the position shown in the drawing.

Although any suitable means, either manually or automatically operated, may be employed for moving rod 47 for the purpose of engaging driving clutch jaw 33 with the engine clutch jaw 34, it is preferable to employ automatic means for this purpose which are so designed as to be operable only when the flywheel 8 has reached a predetermined speed of rotation thereby insuring that a sufficient supply of energy has been stored in the inertia member for the starting operation. In the form shown in the drawing, the automatic means comprises a governor mechanism operated by centrifugal force and drivably connected with flywheel 8 for actuation thereby. Referring now to Figs. 1 and 3, a shaft 53 is rotatably journaled in the lower portion of casing 4 and is provided with a pinion 54 formed integral therewith which meshes with gear 21 thereby providing a driving connection for shaft 53 from flywheel 8 through pinion 14, gear 17, pinion 20, gear 21, and pinion 54. Shaft 53 is provided with a straight splined portion 55 on which is mounted the correspondingly splined hub 56 of a plate 57, said hub seating against a shoulder 58 formed by one side of pinion 54. A plate 59 which is mounted on the hub 56 and is suitably secured to plate 57, as by means of a rivet or rivets 60, is provided with diametrically opposite extensions in which are formed elongated slots 61. Another portion of shaft 53 adjacent the straight splined portion 55 is provided with curved splines or threads 62 on which is positioned a correspondingly splined or threaded hub 63 having a flange or collar 64 formed on its outer end, and a circular flange or plate 65 adjacent its inner end. A pair of similar irregularly shaped flyweights 66, provided with forked or bifurcated ends 67 and 68, are each pivoted at diametrically opposite points to the flange 65 by suitable means such as pins 69 extending through the bifurcations 67 and preferably riveted in the flange 65. Pins 70 extend through and are preferably riveted in the bifurcations 68 of each of members 66, and said members 66 are resiliently held inwardly close to the shaft 53 by means of coil springs 71, each extending from a pin 70 of one member 66 to a pivot pin 69 of the other member 66. Flyweights 66 are positioned intermediate the flange 65 and plate 57, and each flyweight is provided adjacent the center of its outer periphery with a hole or opening 72 in each of which is positioned one end of a pin 73, the other end of each pin 73 engaging in the slot 61 in the plate 59. Pin 73 normally rests in the inner end of slot 61, and the plate 59, flyweights 66, and the member 63 and its flange 64 normally, rotate together as a unit with the shaft 53. When the speed of rotation of shaft 53 becomes sufficiently great, as determined by the speed of flywheel 8, so that the tension of springs 71 is overcome and the flyweights 66 move radially outward, pins 73 moving outwardly in slots 61, relative rotation is produced between member 63 and plates 57 and 59, that is, between member 63 and shaft 53, and the splines or threads 62 cause member 63 to move longitudinally to the right as viewed in Figs. 1 and 3 toward the end of shaft 53.

This longitudinal displacement of the member 73

63 may be employed to operate rod 47 by any suitable means. As shown in the drawing, a lever 74 is pivotally supported by any suitable means such as a short shaft 74^a journaled in a 5 bracket 75 formed integral with a portion of casting 4, and is bifurcated at its lower end so as to form a pair of forked arms 76 which embrace the outer end of member 63 and are held in a groove formed in the surface of said member between 10 flange 64 and a similar flange 77. The upper arm of lever 74 is provided with an elongated slot 78 which is engaged by a pin 79 secured in any suitable manner as by riveting to the outer end of the enlarged portion of rod 47. When the 15 shaft 53 reaches a predetermined speed of rotation, which is directly proportional to the speed of flywheel 8, the flyweights 66 move radially outward, and member 63 moves longitudinally to the right as viewed in Figs. 1 and 3, and through 20 the medium of collar 77 and the bifurcated portion of lever 74 rotates said lever about its pivot which by means of the pin and slot connection shown at 78, 79 moves rod 47 longitudinally to the left thereby moving clutch jaw 33 into engagement 25 with clutch jaw 34, as previously described. After the engine has started under its own power and the flywheel 8 has slowed down, flyweights 66 will be drawn in toward shaft 53 by springs 71 thereby drawing member 63 to the 30 left and returning rod 47 and clutch jaw 33 to their original disengaged position by the action of flange 64 on the bifurcated portion of lever 74. A spring (not shown) is also preferably provided around shaft 74^a which acts in a well-known manner to resiliently urge lever 74 toward its normal position as shown in Fig. 1.

Referring now to the means for actuating and storing energy in flywheel 8 of the starting mechanism above described, it is desirable that such actuating means be not only simple and efficient in operation, but also that it be reliable under all conditions of operation. It is preferable that such means be entirely independent of any extraneous source of energy such as an electric battery or a supply of compressed air, and accordingly the present embodiment discloses the use of a double acting fluid pressure engine, the motive fluid for which is generated by an automatic pistol means producing a succession of explosions which is drivably connected with the flywheel 8 through a suitable train of reduction gearing, and also through a one-way driving connection so that the flywheel may be driven by the engine but energy cannot be transmitted from the flywheel back to the engine. In the form shown, a single cylinder double acting fluid pressure engine is employed which is housed and supported in a suitable casing 80 which is secured to main casing 4 in any preferred manner. A cylinder block 81 provided with the usual fluid passages 82 and 83 and exhaust passage 84 is 55 removably secured to casing 80 by any suitable means such as screws 85. A piston 86 having a rigid piston rod 87 reciprocates in cylinder 81, the piston rod 87 extending downwardly through the upper portion of casing 80 through a stuffing box 88 into a crank case 89 wherein the lower end of piston rod 87 is drivably connected to the upper end 90 of a connecting rod 91 by means of the 60 usual wrist pin 92. Connecting rod 91 is secured in any suitable manner to a crank pin 93 which forms an integral portion of a crank shaft 94 rotatably supported in bearings formed in casing 80. The inner end of crank shaft 94 extends 65 within main casing 4 and is provided with a

pinion 95 secured thereto by any suitable means such as a double-D 96 and a slotted lock nut 97, said pinion 95 meshing with a similar pinion 98 which is formed integral with the outer end of hollow shaft 23, previously referred to. 5

Shaft 23, which is rotatably supported within casing 4 by means of ball bearings 99, retained in a suitable boss 100 by means of an annular recess plate 102 and a lock nut and washer 103, and by a bushing 101 positioned within the face 10 of barrel member 26, is adapted to transmit the rotation of crank shaft 94 of the fluid pressure engine to the flywheel 8 through a suitable train of reduction gearing and through a one-way driving connection. In the form shown, the 15 train of reduction gearing comprises a portion of the gear train previously described as forming the driving connection between flywheel 8 and barrel member 26, namely gear 21, pinion 20, gear 17 and pinion 14, while the one-way 20 driving connection is constituted by a roller clutch interposed between a portion of shaft 23 and the hub 22 of gear 21. This roller clutch, which is shown more clearly in Fig. 2, is of the usual type and comprises a plurality of elongated 25 rollers 104 which are held between the inner surface of hub 22 of gear 21 and the outer surface of a portion of shaft 23 intermediate its ends in which there are provided a plurality of grooves 105 in which the rollers 104 rest. Each 30 groove 105 is so shaped as to provide a deep portion and a shallow portion, the respective depths being such that when the rollers 104 are in the deep portion of grooves 105, hub 22 may rotate freely about shaft 23, but when they are moved toward the shallow end of the grooves they become tightly wedged between hub 22 and shaft 23 and form a driving connection therebetween. The normal position of rollers 104 when both 40 shaft 23 and hub 22 are at rest is as shown in Fig. 2, at the deep ends of grooves 105, and in this position rollers 104 are resiliently urged outward into frictional engagement with the interior of hub 22 by means of small coil springs 106 which are contained in suitable recesses 107 formed in 45 shaft 23. The direction of rotation of both shaft 23 and hub 22 is clockwise as viewed in Fig. 2 so that, with both members at rest, if shaft 23 is started rotating due to its engagement with crank shaft 94 of the fluid pressure engine, rollers 104 50 will tend to move out of the deep portion of groove 105 and to be wedged between shaft 23 and hub 22 thereby forming a driving connection between these members which is adapted to transmit torque from crank shaft 94 to flywheel 8. 55 When shaft 23 is stopped, or the speed of flywheel 8 becomes such that the speed of rotation of hub 22 is greater than that of shaft 23, rollers 104 will again be moved to the deep ends of grooves 105 and hub 22 will rotate freely about 60 shaft 23 upon rollers 104 as its bearings. Rotation of crank shaft 94 can therefore be transmitted to flywheel 8 through shaft 23, the roller clutch and the reduction gearing, but due to the overrunning action of the clutch, rotation of flywheel 8 cannot be transmitted in the reverse 65 direction to crank shaft 94.

In order to avoid dependence upon the more usual sources of fluid under pressure, automatic pistol means have been provided for generating 70 the high pressure fluid which acts as the motive force for the fluid pressure engine employed in the starter herein disclosed. As shown in Fig. 1, the automatic pistol means, which, by firing a succession of explosive cartridges generates a sup- 75

ply of high pressure fluid, is the same mechanism which is disclosed in Patent No. 1,572,998 issued to Rex Harris on February 16, 1926, and for that reason has not been shown nor described in detail herein. In general, however, the automatic pistol mechanism, indicated generally by reference character 108, comprises a magazine containing a plurality of explosive cartridges, a cartridge chamber, a barrel containing a bore, and firing and cartridge ejecting means, all of which are automatically actuated by means of an operating bracket member 109 which is given a reciprocating movement by a cam 110 driven by the crank shaft 94 of the fluid pressure engine through a suitable train of reduction gearing. In the form shown, the outer end of crank shaft 94 is provided with a pinion 111 secured thereto in any suitable manner as by means of a double-D 112 and a lock nut 113, said pinion meshing with a plurality of planetary gears 114, preferably three in number, which in turn engage a stationary internal ring gear 115 secured to casing 80 by any suitable means such as screws 116. Planetary gears 114 are rotatably mounted on a carrier plate 117 on bearings provided by bushings 118 which surround sleeves 119 placed over screws 120 which are threaded into carrier plate 117. An annular spacing ring 121 is provided for holding planetary gears 114 in their proper operative position. Carrier plate 117 is provided on its outer face with an integral stub shaft 122 which is rotatably supported in ball bearings 123 which are held by means of a retaining plate 124 and screws 125 within a boss 126 formed in a cover plate 127 which is secured to casing 80 by any suitable means such as bolts 128. The outer end of shaft 122 extends beyond cover plate 127 and is provided adjacent its extremity with a cam 110 which is drivably secured thereto by any suitable means such as a key 130 which is formed integral with a collar 131 on shaft 122 against which cam 110 is held by a nut 132. A roller 133 rotatably supported within the lower bifurcated portion of bracket operating member 109 bears upon cam 110 and, as the latter rotates, transmits a reciprocating motion to member 109. A spring 134 is provided which bears against the upper end of member 109 thereby tending to maintain roller 133 in operative relation with cam 110 at all times. The reciprocating motion of operating member 109 is transmitted through suitable mechanism as described in Patent 1,572,998, so as to automatically perform the functions of loading, cocking, firing and ejecting the fired cartridges from the automatic pistol mechanism above described.

The fluid under pressure which is generated by the automatic pistol mechanism 108 is supplied through a passage 135 to the valve chest 136 of the fluid pressure engine from whence it is admitted to cylinder 81 at the proper time by means of fluid passages 82 and 83 and a slide valve 137 of the usual D-type employed in double-acting engines. Valve 137 is operated in proper relation to piston 86 by any suitable means such as that shown herein which comprises a yoke 138 encircling a portion of valve 137, said yoke having a stem 139 the lower end of which is threaded into the upper end of a sleeve 143, the latter having a bifurcation in which a rod 140 is pivotally connected by pin 144. The opposite end of the rod 140 is provided with a yoke portion 141 encircling a cam 142 formed on crank shaft 94. Cam 142 is so shaped with respect to the position of crank pin 93 of the crank shaft 94 that

slide valve 137 will be operated in the well-known manner so as to properly distribute the fluid under pressure to cylinder 81 for the purpose of operating the fluid pressure engine.

Describing now the operation of the present invention, it will be assumed that all parts of the starter mechanism are at rest and in the positions shown in Fig. 1. A supply of cartridges having been loaded in the magazine of the pistol mechanism and the firing device locked, as described in Patent No. 1,572,998, the fluid pressure engine is next placed in proper starting condition by rotating crank shaft 94 until a firing position of the piston mechanism is reached when piston 86 will be at one end of its stroke and one of the fluid supply passages 82 or 83 will be in full communication with valve chest 136. Suitable means are provided for accomplishing this preliminary step in the starting operation which, in the form shown, comprise a pair of bayonet slots 145 formed in the hollow outer end of shaft 122 which are adapted to receive the lugs of an ordinary hand crank. A suitable indicator such as a pointer 146 which is held on shaft 122 between cam 110 and nut 132 is also provided to show when the starter parts are in proper position for starting.

The pistol mechanism is then unlocked and fired as described in Patent No. 1,572,998 and the explosion of the cartridge generates a fluid under high pressure which passes through passage 135 to valve chest 136 and thence to cylinder 81 of the fluid pressure engine and the latter is started. It will be understood that from this time on until either all the cartridges contained in the magazine of the automatic pistol means are exhausted, or until the pistol means is rendered inoperative by the operator, successive explosions will be automatically produced by the rotation of crank shaft 94 which is transmitted through the reduction gearing and cam 110 to the pistol operating member 109. Flywheel 8 is then rotated and energy is stored therein due to the driving connection between crank shaft 94 of the fluid pressure engine and shaft 11 of the flywheel, as previously described. Driving clutch jaw 33 is also rotated by crank shaft 94 during the acceleration period of flywheel 8 through the engagement of pinion 24 formed on the hub 22 of gear 21 with planetary gears 25. Flywheel 8 continues to be accelerated by the torque of crank shaft 94 until it reaches a speed at which it tends to drive gear 21 faster than the latter is driven by shaft 23 through the roller clutch, at which time the overrunning action of said clutch takes place and gear 21 rotates freely upon shaft 23. At this time, driving clutch member 33 also ceases to be driven by crank shaft 94 and receives its rotation from flywheel 8. At the same time the rotation of flywheel 8 is being transmitted through gear 21 and pinion 54 to governor shaft 53, and, as previously described, when the speed of rotation of flywheel 8 reaches a predetermined amount, flyweights 66 of the governor mechanism fly out from shaft 53 and, through member 63 and lever 74 cause rod 47 to be moved to the left and to effect engagement of driving clutch jaw 33 with engine clutch jaw 34. The engine to be started is then cranked by the application to driving clutch jaw 33 of the energy which has been stored in the rapidly rotating flywheel 8. When the engine to be started starts under its own power, clutch jaw 34 overrides the teeth of clutch jaw 33 and due to their inclined surfaces forces jaw 33 back out of engagement. Should a

backfire occur during the starting operation, the friction clutch comprising friction discs 36 will operate to allow relative movement between the interiorly threaded nut 35 and driving barrel 26 thereby protecting the parts of the starter from injury. After the engine to be started is operating under its own power, the automatic pistol means may be rendered inoperative by the operator, if it has not already ceased to function due to exhaustion of the supply of cartridges. The fluid pressure engine will also cease to operate when the pistol mechanism is stopped, and as the flywheel 8 runs down, rod 47 will be fully withdrawn as previously described and all parts will be returned to their original positions as indicated in Fig. 1.

There is thus provided by the present invention an inertia starter which is simple and rugged in construction and particularly reliable in operation due to the provision of novel means for actuating said starter which are entirely self-contained and which do not depend upon extraneous sources for their motive power. The inertia member of the starting mechanism disclosed in the present invention is adapted to be accelerated by a novel type of fluid pressure engine through suitable gearing and a one-way clutch which allows torque to be transmitted from the fluid pressure engine to the inertia member but prevents its transmission in the opposite direction. The fluid pressure engine does not require the installation of an air compressor or other similar equipment for supplying a fluid under pressure, but is provided with an automatic pistol mechanism for this purpose, which, by the firing of successive explosive cartridges, generates a sufficient supply of fluid under pressure for operation of the fluid pressure engine, which feature makes this starter particularly well adapted for airplane usage. The starter herein disclosed is also provided with means for automatically engaging the starter clutch jaw with a member of the engine to be started when the inertia member of the starting mechanism has reached a predetermined speed of rotation which assures that a sufficient supply of energy has been stored therein for the starting operation.

It will be obvious that the invention is not limited to the specific forms described and illustrated in the drawing, but is capable of a variety of mechanical embodiments. For instance, any suitable fluid pressure engine may be substituted for the one disclosed herein, and any suitable automatic pistol means might be substituted for that shown by the Harris patent. It will also be understood that manual means may be employed for actuating rod 47 and causing engagement of the starter clutch jaw with that of the engine to be started. Various other features, which will now appear to those skilled in the art, may be made in the form, details of construction, and arrangement of the parts without departing from the spirit of the invention.

What is claimed is:

- 65 1. Engine starting mechanism including an inertia member rotatable at high speed, an engine engaging member movable into engaging position after acceleration of said inertia member to high speed, actuating means for said inertia member including a crankshaft having a gear train at each end thereof, means including a roller clutch for connecting one of said gear trains with said inertia member to accelerate the latter, means for liberating energy from an explosive charge to rotate said crankshaft, and means driven from
- 5 the gear train at the opposite end of said crankshaft for liberating additional energy to continue the rotation of said crankshaft and thereby further accelerate said inertia member.
2. Engine starting mechanism including an inertia member rotatable at high speed, a crankshaft, means for liberating energy to actuate said crankshaft, means connected with one end of said crankshaft to transfer the energy thus liberated to said inertia member, and means connected with the opposite end of said crankshaft for liberating additional energy to continue the rotation of said crankshaft and thereby accelerate said inertia member. 5
3. Engine starting mechanism including an inertia member rotatable at high speed, a crankshaft, a cartridge firing mechanism, a cylinder adapted to receive the expanding gases generated by the firing of a cartridge in said mechanism, a piston in said cylinder operatively connected with said crankshaft, means connected with one end of said crankshaft to transfer energy to said inertia member, and means connected with the opposite end of said crankshaft for actuating said cartridge firing mechanism to liberate additional 10 energy to continue the rotation of said crankshaft and thereby accelerate said inertia member. 15
4. Engine starting mechanism including an inertia member, an engine engaging member, a gear train connecting said members, an explosive charge receiving chamber, means for firing a charge in said chamber, means including a portion of said gear train for transferring to said inertia member the energy liberated from the fired charge, such transfer of energy acting to accelerate said inertia member sufficiently to operate said engine engaging member, and means for providing a one-way driving connection between said last named portion of said gear train and said inertia member. 30
5. Engine starting mechanism including an inertia member, an engine engaging member, a gear train connecting said members, an explosive charge receiving chamber, means for firing a charge in said chamber, means including a portion of said gear train for transferring to said inertia member the energy liberated from the firing charge, such transfer of energy acting to accelerate said inertia member sufficiently to operate said engine engaging member, means for providing a one-way driving connection between said last named portion of said gear train and said inertia member, and means movable axially and centrally of said one-way driving connection to move said engine engaging member into engine 35 engaging position. 40
6. Engine starting mechanism including an inertia member rotatable at high speed, an engine engaging member movable into engaging position after acceleration of said inertia member to high speed, an explosive charge receiving chamber, means for firing a charge in said chamber, and means for transferring to said inertia member the energy liberated from the fired charge, such transfer of energy acting to accelerate said inertia member sufficiently to move said engine engaging member into engaging position. 50
7. Engine starting mechanism including an inertia member rotatable at high speed, an engine engaging member movable into engaging position after acceleration of said inertia member to high speed, means for firing an explosive charge to liberate energy for storage in said inertia member to accelerate the latter, and means rotatable with said inertia member to cause a second explo- 7

- sive charge to be fired and thereby liberate additional energy for storage in said inertia member.
8. Engine starting mechanism including an inertia member rotatable at high speed, an engine engaging member movable into engaging position after acceleration of said inertia member to high speed, means for firing an explosive charge to liberate energy for storage in said inertia member to accelerate the latter, means rotatable with 10 said inertia member to cause a second explosive charge to be fired and thereby liberate additional energy for storage in said inertia member, and means for subsequently transmitting the energy thus stored in said inertia member to the engine.
- 15 9. Engine starting mechanism including an in-

ertia member rotatable at high speed, an engine engaging member movable into engaging position after acceleration of said inertia member to high speed, means for firing an explosive charge to liberate energy for storage in said inertia member to accelerate the latter, means rotatable with 5 said inertia member to cause a second explosive charge to be fired and thereby liberate additional energy for storage in said inertia member, and means including a one-way clutch interposed between 10 said firing means and said inertia member for limiting the amount of energy transferable to said inertia member.
